PORTABLE WINCH

David B. Hoffman, Columbus, Ohio

Application April 16, 1957, Serial No. 653,239

7 Claims. (Cl. 254—167)

My invention relates to a portable winch. It has to do, more specifically, with a portable hand-operated reversible winch or windlass. The type of portable winch to which my invention is applicable is commonly known commercially as a power puller and hoist.

Winches of this type basically include a rotatable cable spool or drum which is rotated in a cable winding direction by means of an oscillatory lever through the medium of pawl and ratchet mechanism associated with the lever and drum. Reversing mechanism is associated with the ratchet mechanism to provide for adjustment of such mechanism to permit reverse rotation of the drum in a cable unwinding direction.

In the prior art devices, various types of reversing mechanisms have been so designed that they interfere with the efficient operation of the winch when the drum is rotated in a cable winding direction. In one prior art device, this is due to the fact that the reversing mechanism is so designed that it limits the lever action while the drum is being advanced in a cable winding direction. Furthermore, the reversing mechanisms of prior art winches are usually complicated and sensitive, including many parts, such as springs, which can be easily sprung or otherwise damaged to make the reversing action of the mechanism ineffective. This is especially true in the type of prior art machine indicated above in which the lever action in pulling is limited by the reversing mechanism and such mechanism bears the full brunt of the force applied to the lever which can cause distortion of such mechanism so that it will not be positive in action and may be completely ineffective.

It is one object of my invention to provide a pulling winch or hoist of the portable type which is provided with reversing mechanism of such a nature that it will not interfere with the efficient operation of the oscillating lever and ratchet and pawl mechanism during rotation of the drum in a cable winding direction.

Another object of my invention is to provide a reversing mechanism for a winch of the type indicated which is extremely simple, positive, and foolproof, being composed of a minimum number of simple parts which act positively or will work freely without chance of distortion by the force applied to the lever.

Other objects will be apparent.

According to my invention, I provide a winch which includes a rotatable drum having pawl and ratchet mechanism which is actuated by oscillation of an associated lever or handle to rotate the drum. The pawl and ratchet mechanism includes a feed pawl and a stop pawl. A simple spring arrangement is provided for setting the feed pawl for rotation of the drum in a forward or cable winding direction or in a reverse or cable unwinding direction. To cause the feed pawl to function in a forward or a reverse direction a single simple cam is associated with the drum. This single cam not only functions to assist in engaging the feed pawl to cause it to act as a stop pawl with the ratchet in a reversing di-

2

rection but also serves immediately thereafter to disengage the stop pawl to permit the reversing movement of the ratchet and drum under control of the feed pawl. The cam will in no way restrict oscillation of the lever and will not need to bear the load on the lever and drum during either the forward or reverse operation of the drum and, therefore, will not become distorted.

In the accompanying drawings, I have illustrated one example of my invention but it is to be understood that specific details may be varied without departing from the basic principles of my invention.

In these drawings:

Figure 1 is a longitudinal sectional view taken along line 1—1 of Figure 4 through a winch which embodies my invention.

Figure 2 is a plan view of the yoke which carries the feed pawl and the spring which controls the position thereof.

Figure 3 is a detail in section taken along line 3—3 of Figure 4 showing the reversing cam in the inoperative position it occupies during the pulling or power applying operation of the winch.

Figure 4 is a plan view, partly broken away, of the entire winch.

Figure 5 is an enlarged vertical sectional view taken along line 5—5 of Figure 4 illustrating the action of the reversing mechanism including the reversing cam.

With reference to the drawings, I have illustrated in Figures 1 and 4 the general structure of the winch or power puller and hoist in which my invention is embodied.

This winch includes a frame 10 of elongated form which is of substantially rectangular outline but has the converging ends 11 and 12. The end 12 is provided with an anchoring hook 13 for anchoring the frame to a suitable support whereas the end 11 is provided with a depending cable guide 14 through which the cable 15, which is to be wound on the winch, is passed. This cable may be part of a block and tackle arrangement for pulling or raising a suitable load. It is to be understood that although I refer to a cable, my winch is applicable to pulling on a rope or even a chain or other flexible member which can be wound on the drum of the winch.

Transversely disposed within the frame 10 and mounted for rotation on the frame is the spool or drum 16. The drum 16 is provided with trunnions 17 which are rotatably disposed in bearing openings in the sides of the frame 10. Directed chordally (Figure 4) through the drum 16 is a socket 18 for receiving the end of the cable. This end of the cable is anchored in the socket 18 by means of a pointed anchoring plug 19 which is threaded radially through the surface of the drum through a radial bore 20 into the socket 18 so as to engage the cable, it being apparent that the bore 20 is at right angles to the socket 18. Also associated with the drum is a cable guide in the form of an upstanding leaf spring 21 (Figure 1) which is disposed within the sides of the frame, extending from one side to the other, and is spaced from the periphery of the drum as shown in Figure 1. This upstanding leaf spring 21 is carried by a U-shape bracket 22 which depends from the sides of the frame and is secured thereto. This guide will aid in proper positioning of the cable as it winds on the drum. Above the bearing openings for the drum trunnions 17, the frame 10 is provided with the upstanding yoke bearings 25, as shown best in Figures 1, 3 and 4. These bearings receive the pivots 26 which are provided for the yoke 27. The yoke 27 straddles the frame 10 with its lower ends disposed outside the adjacent bearings 25. The yoke 27 is provided with a socket 28 for receiving the lower end of a handle or lever 29 which may be secured therein by means of a cotter key 30.

It will be noted best from Figures 1 and 3 that the

yoke pivot points 26, which are the fulcrum for the lever 29, are disposed eccentrically relative to the axis of trunnions 17 of the drum 16.

On each end, the drum is provided with an integral ratchet wheel 31. For cooperating with this ratchet wheel, the yoke 27 carries the feed pawl 32. This feed pawl is a double pawl so that it will cooperate with both ratchet wheels 31 and includes a central transverse sleeve 33 (Figure 2) through which is passed a pivot pin 34 that extends through openings formed in the sides of the yoke 27. One arm of the pawl is provided with a narrow tooth 35 for engaging the teeth of the associated ratchet wheel 31 and the other arm is provided with a wide tooth 36 which engages the teeth of the associated ratchet wheel 31 but which also extends outwardly therebeyond to provide a cam-engaging extension 37.

In order to set the feed pawl 32 in either of two positions, an off-center spring arrangement is provided as shown best in Figures 1, 2, 3 and 5. In one position, the feed pawl will be set to engage the teeth of the ratchet wheels 31 for rotation of the drum in a forward or cable-winding direction and in the other position, the pawl will be set to permit reverse rotation of the drum in a cable-unwinding direction. This spring includes a wire spring 40 which is bent in a flat plane and is pivoted inside the yoke at 41 for pivotal movement in a plane at right angles to the plane of bend of the spring. The free end 42 of the spring is disposed between a pair of lugs 43 and 44 which project radially from the pawl 32, the pawl being provided with a cam surface 45 of arcuate form between the lugs and with which the spring end 42 resiliently engages.

When the spring 40 is swung to the off-center position shown in Figure 3, the end 42 thereof engages the lug 44 of the pawl and springs the pawl clockwise as viewed in Figure 3 to cause the pawl to engage the teeth of the ratchets 31 so that when the yoke is swung towards the right in Figure 3, the drum 16 is rotated in a cable-winding direction. On the other hand, when the off-center spring 40 is swung in the opposite direction to engage the lug 43 of the pawl, as shown in Figure 5, the pawl is rotated in a clockwise direction as viewed in this figure until the lug 43 strikes a stop pin 46 which is provided on the adjacent side of the yoke 27. This will swing the pawl teeth 35 and 36 away from the teeth of the ratchet wheels 31 to permit the yoke 27 to swing in a counter-clockwise direction as viewed in Figure 5 without having the pawl teeth 35 and 36 engage the ratchet wheel until towards the end of the stroke when the reversing cam 50 functions as shown in Figure 5. The action of this cam will be explained later.

In addition to the feed pawl 32, I have provided the stop pawl 51 which normally prevents reversing movement of the ratchet wheels 31, as indicated in Figure 3. This pawl 51, as shown best in Figures 3, 4, and 5, comprises a tubular or sleeve section 52 through which a pivot pin 53 passes. The end of this pin 53 is disposed in upstanding bearings 54 provided on the sides of the frame 10 in longitudinally spaced relationship to the upstanding yoke bearings 25. This pawl 51 is a double pawl and is provided with teeth 55 and 56 on its arms for cooperating with the teeth of the ratchet wheels 31 so as normally to prevent reverse movement of the drum. A torsion spring 57 is anchored to the frame at 58 and surrounds the sleeve 52 of the pawl to which it is anchored so as to serve to normally swing the pawl towards the ratchet wheels 31 to engage the pawl teeth 55 and 56 with the ratchet teeth to prevent reverse rotation of the drum. The pawl sleeve 52 is provided with a radially extending handle 52a by means of which the stop pawl may be manually disengaged from the ratchet wheels 31 by overcoming the force exerted by the spring 57. Associated with the pawl tooth 56 is an outwardly projecting cam-engaging lug 59.

It will be noted best from Figure 3 that the yoke 27

carries a stop lug 60 at each side thereof which will engage with a stop edge 61 formed on the upstanding pawl bearing 54 at the corresponding side of the frame 10. These stops will provide a positive means for limiting the swinging of the yoke 27 clockwise, as viewed in Figure 3, which is the direction in which it is swung during the forward advancing of the drum 16 to wind the cable.

The reversing cam 50, previously referred to, is a simple cam plate which is mounted at one side of the frame 10 between one of the yoke bearings 25 and the adjacent end of the drum 16. The cam 50 is pivoted at 62 to the frame and is normally swung into contact with the trunnion bearing 17a on the corresponding end of the drum 16 by means of a tension spring 63 which is connected to the lower end of the cam plate at 64 and which is anchored to the side of the frame 10 at 65. The cam 50 is provided with an upwardly extending cam lug 66 which will act to release the stop pawl 51 from the ratchet wheels 31 and with an upstanding cam lug 67 which will function to return the cam to the position shown in Figure 3 and permit reengagement of the stop pawl 51.

In the operation of the winch, the reversing cam 50 will function as indicated below. Normally, during the power applying or forward rotation of the drum 16, the cam 50 will function as indicated in Figure 3. The spring 40 will be set as shown in Figure 3 so that the teeth 35 and 36 of the feed pawl 32 will be held in resilient contact with the teeth of the ratchet wheels 31. Consequently, as the lever 29 and yoke 27 are swung in a clockwise direction as viewed in Figure 3, the drum 16 will be rotated in a cable-winding or forward direction. The yoke 27 will swing in the forward direction until the stops 60 thereon contact the stops 61 on the frame 10. During this swinging action, the adjacent tooth 36 and cam-engaging extension 37 thereof provided on the feed pawl 32 will miss the upstanding cam lug 67, as indicated in Figure 3. However, the extension 37 will engage the cam lug 66 and rotate the cam clockwise slightly and the cam lug 66 will contact the pawl lug 59 on the stop pawl 51 so as to release the stop pawl from the ratchet wheels 31 but the feed pawl 32 will be in engagement with the ratchet wheels 31 at this time. This motion of the cam at this time is a lost motion as it performs no desired function during the pulling stroke of the lever 29. However, this lost motion will not occur as the operator becomes experienced with operation of the machine and stops swinging of the lever 29 short of the point where the feed pawl 32 contacts the cam 50. Shortly after rotation of the cam the stops 60 and 61 engage with each other to limit movement of the lever 29. It will be noted that during this pulling movement of the lever 29, the pawl extension 37 will miss the stop 61 at the corresponding side. Reverse swinging movement of the lever 29 will cause the extension 37 to engage the cam lug 67 and return the cam to its original position. Thus, unrestricted movement of the yoke 27 and lever 29 during the pulling action will be permitted by the reversing cam 50 and oscillations of these members will move the drum 16 in a forward pulling or cable-winding direction.

To reverse the rotation of the drum 16, it is merely necessary to reset the spring 40. The spring is moved to the position shown in Figures 1 and 5. This, as shown by the broken lines in Figure 1, will throw the teeth of the feed pawl 32 outwardly away from the teeth of the ratchet wheels 31. Consequently, when the yoke 27 and lever 29 are swung counterclockwise as viewed in Figure 1, the feed pawl will not engage the ratchet wheels 31. At this time, the stop pawl 51 is still in engagement with the ratchet wheels 31 to prevent reverse rotation of the drum 16, it being understood that there is a load on the cable 15 which has been wound on the drum. The feed pawl 32 will not engage the ratchet wheels 31 again until the tooth extension 37 of the pawl engages the inclined stop surface 61 at the same side

which will force it inwardly over the edge of the cam lug 66 with which it will engage. Due to the outward position of the pawl 32, the extension 37 will first engage the cam lug 66 adjacent its outer end and will therefore rotate it about its pivot 62, and as the yoke 27 continues to swing, the extension 37 will follow the edge of the lug 66 inwardly causing the teeth of the feed pawl to engage with the ratchet wheels 31. As shown in Fig. 5, the edge of the cam lug 66 assists in causing the teeth of the feed pawl 32 to engage with the ratchet wheels 31, but basically the inclined stop surface 61 of the frame and the adjacent vertical edge of the corresponding bearing 54 of the frame would guide the extension 37 and force the teeth of the feed pawl to engage the ratchet wheels 31 at the desired point even if the cam were not there. After the teeth of the feed pawl 32 engage the ratchet wheels 31 and cause the feed pawl to pick up the load, the cam 50 will continue to rotate until its lug 66 engages the stop pawl lug 59 and swings the stop pawl teeth 55 and 56 out of contact with the ratchet wheels 31. The cam 50 will be rotated by engagement of the extension 37 with the adjacent edge of the cam lug 66 about the pivot 62 until the notch 68 provided in the opposite edge of the cam lug 66 receives the lug 59 on the pawl 51 which will serve to lock the cam in the position shown in Figure 5. At this time, the stop pawl 51 will be completely disengaged from the ratchet wheels 31. However, since the teeth of the feed pawl 32 were forced into engagement with the ratchet wheels 31 and the feed pawl picked up the load before the stop pawl 51 was disengaged from the ratchet wheel, the feed pawl will now serve as a stop pawl to prevent reverse motion of the drum 16 until the yoke 27 and lever 29 are swung in the opposite direction. At this time, the lever 29 and yoke 27 will be in the full line position shown in Figure 1.

If the lever 29 and yoke 27 are now swung in a clockwise direction as viewed in Figures 1 and 5, the reverse movement of the feed pawl 32 will cause the extension 37 thereof to engage the cam lug 67 and swing the cam 50 clockwise about the pivot 62 thereby unlocking it and permitting the stop pawl 51 to again engage the ratchet wheels 31. However, before this engagement, the ratchet wheels 31 will have reversed to the extent of one tooth. The feed pawl 32 cannot move away from the cam 50 holding the stop pawl 51 away from the ratchet wheels 31 without first releasing the cam and permitting the pawl 51 to lock the ratchet wheels 31 again before the feed pawl is released from the ratchet wheels 31.

My winch provides for simple positive and foolproof reversing action in conjunction with a double leverage construction. The double leverage results from the fact that the lever 29, the yoke 27 and the feed pawl 32 are pivoted at the pivots 26 which are located on a different spaced axis from the axis of the trunnions 17 on which the ratchet wheels 31 and drum 16 are mounted. The leverage of the pawl 32 acting against the ratchet wheels 31 and the leverage of the drum 16 against the cable 15 thereby multiply the mechanical advantage of the winch. The reversing mechanism is extremely simple comprising a spring-held single cam and one adjustable bias spring. The cam is pivoted about an axis independent of the drum axis and is so disposed that it will not interfere with the normal oscillation of the lever for rotating the drum in a forward direction. The cam is positive in action, however, when the feed pawl is biased into position to operate the reversing mechanism. The cam is not subject to any of the load applied to the drum and, therefore, will not be distorted by such force. Distortion is further prevented by the provision of the positive stops between the lever yoke and the frame. The cam is free and positive in action with good mechanical advantage in applying the force of the feed pawl, which actuates it, to the stop pawl, and good mechanical ad-

vantage when the stop pawl and associated spring are aiding in moving the cam out of locking position and when the cam spring is holding the cam clear of the feed pawl during the forward movement of the drum. The cam action is absolute and positive. It is impossible to lose the load unless the machine breaks or the operator intentionally releases the load by manually lifting the stop pawl from the ratchet wheels.

According to the provisions of the patent statutes, the principles of this invention have been explained and have been illustrated and described in what is now considered to represent the best embodiment. However, it is to be understood that, within the scope of the appended claims, the invention may be practiced otherwise than as specifically illustrated and described.

Having thus described my invention, what I claim is:

1. A winch of the type described comprising a rotatable drum having ratchet means associated therewith, a lever oscillatable to actuate said ratchet means to rotate the drum, said ratchet means comprising a ratchet wheel fixed to the drum, a feed pawl carried by the lever, means for adjusting the feed pawl on the lever to an advancing position where it engages the teeth of the ratchet wheel so that oscillation of the lever will rotate the drum in a forward direction or to a reversing position where it is spaced from the ratchet teeth so that oscillation of the lever will not rotate the drum in a forward direction but will permit reversal thereof, a stop pawl engaging the teeth of the ratchet wheel to prevent reverse rotation of the drum as it is advanced in a forward direction, fixed cam means adjacent the path of movement of the lever for engaging the feed pawl upon swinging of the lever in a forward direction only when the feed pawl is set at reversing position to engage the feed pawl with the ratchet teeth to cause it to function as a stop pawl for the reversing movement of the drum, and a cam movably mounted adjacent the ratchet wheel and positively engaged by said feed pawl upon the camming thereof by said fixed cam upon further swinging of the lever in said forward direction to positively move the movable cam into engagement with the stop pawl to thereby release the stop pawl from the ratchet teeth to permit such reversing movement under control of the lever.

2. A winch according to claim 1 including means for locking the movable cam in the said position where it engages the stop pawl and releases it from the ratchet teeth, said means comprising interlocking portions on the said movable cam and the stop pawl, a lug on said movable cam, and means for releasing said interlocking portions, said last-named means comprising a lug-engaging extension on said feed pawl for engaging said lug upon swinging of the lever in a reverse direction to move said cam in the opposite direction to thereby permit the stop pawl to again engage the ratchet teeth.

3. A winch of the type described comprising a frame, a drum rotatably mounted on the frame, a ratchet wheel fixed with the drum for rotation therewith, a lever pivoted to the frame for oscillation, a feed pawl pivoted to the lever for cooperating with the teeth of the ratchet wheel, means for adjusting the feed pawl on the lever about its pivot to an advancing position where it engages the ratchet teeth so that oscillation of the lever will rotate the drum in a forward direction or to a reversing position where it is spaced from the ratchet teeth so that oscillation of the lever will not rotate the drum in a forward direction but will permit reversal thereof, a stop pawl pivoted to the frame and normally engaging the ratchet teeth to prevent reverse rotation of the drum as it is advanced in a forward direction, a cam edge on the frame adjacent the path of movement of the lever serving as a top member which engages the lever to limit swinging in a forward advancing direction and engaged by the feed pawl upon oscillation of the lever only when the pawl is set at reversing position to cause the feed pawl to engage the ratchet wheel and to function as

a stop pawl for the reversing movement, and a cam rotatably mounted on the frame adjacent the ratchet wheel and positively engaged by the feed pawl when it is set in reversing position upon said oscillation of the lever to positively engage the stop pawl to release it from the ratchet wheel to permit such reversing movement of the drum under control of the lever said feed pawl having a cam-engaging portion which upon oscillation of the lever in one direction with the pawl in reversing position first engages the cam edge and then engages the rotatable cam and swings it in one direction about its pivot into engagement with the stop pawl for releasing it from the ratchet and upon swinging of the lever in the opposite direction engages the rotatable cam and returns it to its original position.

4. A winch according to claim 3 in which the means for setting the feed pawl in advancing or reversing position is an off-center spring carried by the lever and engaging the pawl.

5. A winch according to claim 4 in which the spring is bent into loops and is pivoted to the lever for swinging movement in a plane at right angles to the plane of bend, said spring having its free end disposed between positioning lugs carried by said pawl and which are spaced angularly of the pivot thereof.

5.
10
15

20
25

6. A winch according to claim 3 in which the rotatable cam is provided with two cam lugs, one of which is engaged by the feed pawl when it is set in reversing position upon swinging of the lever in drum advancing direction and the other of which is engaged by the feed pawl upon swinging of the lever in drum reversing direction.

7. A winch according to claim 6 in which resilient means is provided for maintaining the rotatable cam in its original position, a locking lug carried by the stop pawl and adapted to be engaged by a locking notch in the edge of the rotatable cam when the cam is moved into engagement with the stop pawl.
